CLAIM

The ornamental design for an assembling toy as shown and described.

DESCRIPTION

FIG. 1 is a front view of an assembling toy of the present invention.

FIG. 2 is a rear view thereof.

FIG. 3 is a top plan view thereof.

FIG. 4 is a bottom plan view thereof.

FIG. 5 is a right side view thereof.

FIG. 6 is a left side view thereof.

FIG. 7 is a front perspective view thereof.

FIG. 8 is a rear perspective view thereof.

FIG. 9 is a front view thereof in an alternate configuration

FIG. 10 is a sectional view thereof taken along section line

10-10 of FIG. 1; and,

FIG. 11 is a sectional view thereof taken along section line 11-11 of FIG. 5.

The broken lines are for the purpose of illustrating portions of the article that form no part of the claim.
